UNITED STATES PATENT OFFICE.

JOSEPH L. LAWRENCE, OF SAN FRANCISCO, CALIFORNIA, ASSIGNOR TO HERZOG ELECTRIC & ENGINEERING COMPANY, OF SAN FRANCISCO, CALIFORNIA, A CORPORATION OF CALIFORNIA.

ELECTRIC HEATER.

Application filed August 15, 1922. Serial No. 581,951.

To all whom it may concern:

Be it known that I, JOSEPH L. LAWRENCE, a citizen of the United States, residing at the city and county of San Francisco and 5 State of California, have invented new and useful Improvements in Electric Heaters, of which the following is a specification.

This invention relates to electric heaters and especially to portable heaters such as 10 employed in heating individual rooms in residences, etc., as distinguished from electric cookers, toasters and the like.

Electric heaters, as generally designed, convert electric energy into heat by passing 15 the current or energy to a conductor having sufficient resistance to produce a desired or predetermined temperature. The heat thus produced is in some instances projected by reflectors, and in other instances 20 by direct radiation and conduction, and again, by air circulation by the heat produced is in most cases so localized that the effect of the heater is only noticeable in the immediate vicinity.

25 The object of the present invention is to generally improve and simplify electric heaters, and especially that type in which air circulation is sought; to provide large heating surfaces which will permit efficient 30 radiation and conduction, and to provide a novel arrangement of the heating elements with relation to their supports and surrounding casing, whereby efficient circulation and distribution of the heated air will 35 be obtained. Further objects will herein-after appear.

The invention consists of the parts and the construction, combination and arrangement of parts as hereinafter more fully described and claimed, having reference to 40 the accompanying drawings, in which—

Fig. 1 is a central, vertical, longitudinal section of the heater.

Fig. 2 is a plan view of the same.

45 Referring to the drawings in detail, A indicates a base member consisting of a rectangular shaped plate 2 provided with supporting legs 3. Supported by the base or plate 2 is a rectangular shaped exterior 50 sheet metal casing 4, and supported by the

casing in turn is a top plate B, which comprises of a rectangular shaped frame section 5 having a downwardly turned flange 6 and a pair of cross bars 7. A pair of end openings 8 is thus formed in the plate and a central opening 9. The side sections of the frame 5 are slightly increased in width as indicated at 10, and they cooperate with the cross bars 7 to form an inner frame to which is attached a rectangular shaped casing 11; 60 said casing being secured to the upper frame plate by means of a bottom plate 12 and tie rods 13. Mounted interior of the casing section 11, and disposed concentric therewith and interspaced therefrom, is a pair 65 of inner casing sections 14 and 15. These casings are supported entirely by the lower plate 12 through means of legs or upright bolts as indicated at 16. In other words direct contact between the lower ends of 70 the inner casing sections 14 and 15 is not made with the bottom plate 12 as a spacing, such as shown at 17, is desired to permit a slight circulation of air for purposes hereinafter to be described. The upper end of 75 the innermost casing indicated at 15 is flanged to form a frame as at 18, and this is covered with a wire mesh or screen 19; the openings 8 at the respective ends thereof being similarly covered with screens as shown at 20. 80

The heating elements employed are disposed within the inner casing 15 as shown in Figs. 1 and 2. They are supported by a central rod 21 and a cross arm 22. The elements employed may be of any suitable 85 character, but consist preferably of nichrome wire wound about lava spools or sleeves such as indicated at 23. The spools or sleeves carrying the windings are hung from the cross bar 22 by attaching the upper terminals of the winding thereto, and the lower ends or terminals of the windings are connected to a pair of upright rods as shown at 24; the rods 21 and 24 being supported by the base plate 2 and insulated therefrom 90 in any suitable manner. These rods serve as conductors for the current and are for this reason connected with a suitable source of current supply not here shown.

95 In operation a circuit is closed through 100

the heating elements or the windings carried by the sleeves 23 in any suitable manner, but these windings, together with the lava sleeves supporting the same, will within a very short time assume a red hot temperature. The heat produced is thrown off by radiation and the surrounding air contained in the innermost casing 15 is thereby heated and discharges upwardly through the screen 19. A slightly evacuated condition is produced in the lower end of the casing 15 and an in rush of air will thus take place from the lower chamber indicated at 30, which is in communication with the atmosphere through the screen covered openings 8. In other words the moment circulation is started air will enter the screens in the direction of the arrows, see Fig. 1; it will then pass through the lower chamber 30 in the direction of the arrows, and will finally discharge upwardly through the innermost casing 15 and escape through the screen 19. Efficient circulation is in this manner maintained and large volumes of heated air will constantly be discharged. The air will not only be heated by radiation, but also by direct contact with the windings and by passing through the interior of the spools or sleeves supporting the same as the lava spools assume substantially the same temperature as the windings supported thereby. A large heating surface is in this manner produced whereby direct contact with the air is permitted, and whereby a large radiating surface is also maintained. This radiation will heat the exposed surfaces of the innermost casing 15 and this will again heat the air by radiation and conduction. This heat should be restricted to the innermost casing and the heating elements proper as interference with efficient circulation of air would otherwise be produced. For instance if any of the heat should be conducted or radiated to such an extent as to heat the casing 11, then a slight upward current would be started in the vertical passages communicating with the openings 8 and practically no circulation of air would take place, but such heating of the casing 11 is prevented due to the fact that the casings 11, 14 and 15 are interspaced and dead air spaces 40 and 41 are formed between the same. If the air in these spaces has any tendency to heat, a slight upward circulation will take place as air can enter these spaces through the lower annular opening 17. The screens indicated at 19 and 20 are merely employed for the purpose of excluding paper particles or to prevent other articles from accidentally entering the casing of the heater, for instance an object dropped through the opening 19 might do considerable damage, particularly if one or another of the heating elements should be

encountered, and it is for this reason that the openings employed are screened.

While certain features of the present invention are more or less specifically illustrated, I wish it understood that various changes in form and proportion may be resorted to within the scope of the appended claims, similarly that the materials and finish of the several parts employed may be such as the experience and judgment of the manufacturer may dictate or various uses may demand.

Having thus described my invention, what I claim and desire to secure by Letters Patent is:—

1. An electric heater, comprising a casing 80 a base plate therefor and forming a closure for the lower end thereof, a top plate carried by the casing having air inlet and discharge openings formed therein, a casing attached to the top plate and interspaced with relation to the base plate, said casing communicating with the discharge opening at its upper end and with the inlet openings at its lower end, a flange secured to the lower end of said last named casing, a second casing 90 supported by the flange and interspaced with relation thereto to form a dead air space, and an electric heating element disposed within said second named casing.

2. An electric heater comprising a casing, 95 a base plate therefor and forming a closure for the lower end thereof, a top plate carried by the casing and having air inlet and discharge openings formed therein, a casing attached to the top plate and interspaced 100 with relation to the base plate, said casing communicating with the discharge opening at its upper end and with the inlet openings at its lower end, a flange secured to the lower end of said last named casing, a pair of interspaced casings supported by the flange and interspaced therefrom, and an electric heating element disposed within the innermost of said last named casings.

3. An electric heater comprising a rectangular shaped casing, a base plate forming a support and a closure for the lower end thereof, a pair of air inlet openings formed at each end of said plate and a central air discharge opening also formed in 115 said plate between the inlet openings, a rectangular shaped casing supported by the top plate communicating at its upper end with the air discharge opening and at its lower end with the air inlet openings, a rectangular shaped bottom plate attached to the lower end of said casing, a rectangular shaped casing supported by said bottom plate and disposed within the second named casing and interspaced with relation thereto and an electric heating element disposed within the innermost of said last named casings.

4. In a heater of the character described the combination with the innermost casing and the base plate, of a vertically disposed rod supported by the base plate, a cross arm on the upper end of said rod, a pair of electrical heating elements suspended one from each end of said arm, a pair of rods disposed in alignment with each of said heating elements and connected with said heating elements, and means for forming a circuit through the central rod and the last named rods to permit the passage of a current through the respective heating elements.

JOSEPH L. LAWRENCE.
